UNITED STATES PATENT OFFICE.

GEORGE W. BLAIR, OF PITTSBURG, PENNSYLVANIA.

DESIGN FOR A LAMP-CHIMNEY.

SPECIFICATION forming part of Design No. 20,680, dated April 21, 1891.

Application filed March 23, 1891. Serial No. 386,140. Term of patent 7 years.

To all whom it may concern:

Be it known that I, GEORGE W. BLAIR, of Pittsburg, in the county of Allegheny and State of Pennsylvania, have invented a new and original Design in Lamp-Chimneys, of which the following is a full, clear, and exact description, reference being had to the accompanying two figures of the drawings, marked Figures 1 and 2, which show in side elevation, partly in vertical section, lamp-chimneys embodying my design.

My invention, which relates to a design for lamp-chimneys, consists in the novel outline shape of the chimney, substantially as hereininafter described, and as shown in the drawings.

The ornamentation of the chimney does not

constitute a feature of limitation of the invention.

The chimney, as shown in the drawings, has a portion *a*, with vertical sidelines, and above it a body portion *b* of larger diameter. Above that the chimney bulges outwardly to form an annular shoulder *c*, above which is the neck *d*. 25

I claim—

The design for lamp-chimneys, substantially as herein shown and described.

In testimony whereof I have hereunto set my hand this 19th day of March, A. D. 1891. 30
GEO. W. BLAIR.

Witnesses:

W. B. CORWIN,
THOMAS W. BAKEWELL.
